UNITED STATES PATENT OFFICE.

EDWARD J. HORN, OF ROYAL OAK, AND FREDERICK LINDHORST, OF DETROIT,
MICHIGAN, ASSIGNEES, TO DETROIT TORCH & MANUFACTURING CO., OF
DETROIT, MICHIGAN, A CORPORATION OF MICHIGAN.

TORCH.

1,287,692.

Specification of Letters Patent.

Patented Dec. 17, 1918.

Application filed July 20, 1918. Serial No. 245,867.

To all whom it may concern:

Be it known that we, EDWARD J. HORN and FREDERICK LINDHORST, citizens of the United States, residing at Royal Oak, county 5 of Oakland, and Detroit, county of Wayne, State of Michigan, respectively, have invented a new and useful Improvement in Torches, of which the following is a specification.

10 This invention relates to blow torches and has for its object a blow torch in which the burner is arranged to cause combustion to take place a considerable way back in the burner and in which the fuel vein is partially located in this combustion chamber so 15 as to efficiently preheat the fuel. The common fault with blow torches to-day is that in a cold wind a great many of them are so chilled that they go out or their operation is 20 made unsteady due to the cold air striking the burner and affecting the fuel.

Another object of our improved burner is to accelerate the flow of the mixing and burning gases so as to make a longer and more intense flame without diminishing materially 25 the size of the flame. This is accomplished by reason of the particular location of the air ports and the shaping of the burner. The location of the ports and the shaping of 30 the burner has been understandingly selected with this object in view. The structure and functions alluded to will more fully appear in the detailed description following.

In the drawings,—

35 Figure 1 is an elevation of the blow torch. Fig. 2 is a longitudinal section of the burner.

Fig. 3 is a section of the burner on the line 3—3 of Fig. 2.

40 Inasmuch as the pump *a*, the reservoir *b*, the priming trough *c* and the burner stem *d* are no part of the invention and belong to the prior art, no further description is necessary.

45 The burner is in the form of a casting comprising a barrel made up of two cylindrical sections *e* and *f* connected by a frusto-conical section *g*. To the bottom of this barrel is integrally connected a screw-threaded neck 50 *h* that screws onto the top of the burner stem *d*. Notice that a vein *i* leads from the interior of this neck to the rear of the burner barrel, where a cross passage *j* connects the vein and leads into a valve chamber *k*. Both

the vein and the cross passage are made by 55 boring and the holes where the tool entered are plugged by screw plugs. The valve chamber contains the usual needle valve *m*, which guards an orifice through which the fuel is projected into the burner barrel. 60

Burner barrels of the cylindrical type are old, and these are perforated for the admission of air into the burner barrel, but so far as we are aware, no really intelligent location of these air orifices have been made 65 with the objects in view that we are now about to describe. It has been recognized that it is advantageous to preheat the fuel taken from the reservoir so as to promote combustion, and various ways of accomplishing this have been proposed. In the ordinary burner the air orifices are so located and of such capacity that combustion only takes place at the very forward end of the burner. Consequently the rear of the burner 70 does not get nearly as hot as it does in the arrangement that we are about to describe.

We have located an annular row of holes *n* at the forward end of the frusto-conical section, and from this row of holes to near the 80 extreme rear of such frusto-conical section there are no air orifices. The first row of holes at the rear is located at about the juncture of the frusto-conical section and the rear cylindrical section and is lettered *o*. 85 Near the back of the cylindrical section is another annular row of holes *p* and at the back of the barrel is a row *q*.

The front annular row of holes *n* does not supply air to support combustion; in 90 fact, it is not intended for that purpose. These holes serve the same purpose that they do in most burners. They allow a certain amount of flame to project through the sides of the burner so as to tend to heat the 95 walls of the burner. The air to support combustion practically all comes through the holes in the rows *o*, *p*, *q*, at the rear of the burner. These are so located that, roughly speaking, the mixing chamber lies 100 largely in the rear cylindrical section and to some extent in the rear part of the frusto-conical section, while the major portion of the frusto-conical section and the front cylindrical section inclose the combustion 105 chamber. The large unperforated extent of the barrel between the front row of holes *n* and the row of holes *o* serves to bring the

combustion zone very far back to the rear of the burner, and the flame reaches far back into the rear of the burner to get the necessary oxygen to support the combustion.

5 This insures a portion of the combustion chamber overlying the vein *i* and consequently very highly heating the vein *i* and the fuel contained in it.

To bring the vein *i* into closer proximity 10 with the heat than has heretofore been the practice and more particularly to enhance the vein area exposed to the heat, the vein is formed directly in the wall of the barrel and a rib *r* projects directly into the barrel of 15 the burner and through this rib the passage-way of the vein is bored. Obviously with this rib projecting into the barrel the heated gases communicate a great deal more heat to the vein than they would with the vein 20 merely subtended from the barrel, for the heated gases in this construction encompass substantially one-half the circumference of the vein, whereas with the vein merely subtended the heated gases are only in contact 25 with a small zone directly over the vein.

From the above explanation it is evident 30 that two causes contribute to the high heating of the fuel passing through the vein, namely, the location of the air orifices to bring the combustion chamber over the vein, and in the second place, the adoption of an inwardly projecting rib with a passage-way through it as a vein to bring the heated gases substantially on three sides of the vein. 35 This results in a burner which can stand a very cold wind without blowing out and which under severe conditions will maintain a steady flame due to this efficient arrangement for the preheating of the fuel.

40 Of course, we are aware that there are limitless ways of preheating fuel in burners of all classes, but blow torches have taken on certain characteristic appearances and there are certain standard lines of construction 45 that must be followed to make an economical and salable blow torch. It is the object of this invention to secure these objects in a way that they have never before been accomplished and yet use the same 50 general construction which is familiar in connection with blow torches.

By using the combination of the forward 55 cylindrical section and the frusto-conical section, the latter being free from air orifices except at its extreme rear, a very decided advantage in the playing of the flame is obtained. In fact, this effectively contributes toward the preheating of the fuel. It is, of course, well known that if a fluid 60 passage-way is tapered that it causes accel-

eration of any fluid that is being projected through the passage-way under pressure. Of course, in order to secure these results the passage-way must not have any eduction ports, for obviously these will tend to slow 65 up the speed of the gases. The majority of the blow torches now are perforated all along the barrel and consequently even by tapering barrels of this character, this advantageous acceleration would not be secured. The object of having this cylindrical section at the mouth of the barrel is so 70 as to direct the flame in sort of a column effect out of the burner, which is necessary to make a successful blow torch for the average work. Merely to taper the burner would not accomplish this purpose for although if the taper was in an unperforated barrel the desired acceleration might be secured, on the other hand the tendency would 75 be to make the flame constrict itself to a point, which is not desirable and suitable in the average blow torch. We find that by using a non-perforated frusto-conical section and combining it with a forward cylindrical section, we get the desired acceleration 80 with its increased intensity of heat and at the same time get the column effect to the projecting flame which is necessary for a blow torch of this character. 85

What we claim is:

1. In a blow torch, a burner formed into a barrel, a neck, a valve chamber, a vein passing through and under the barrel wall to the valve chamber, the said barrel being 90 made up of a pair of cylindrical sections connected by a frusto-conical section with holes near the juncture of the front cylindrical section and frusto-conical section and holes adjacent the rear of the frusto-conical 95 section and in the rear cylindrical section. 100

2. In a blow torch, a burner stem and a burner comprising a casting forming a burner barrel made up of two cylindrical sections connected by a frusto-conical section 105 with holes located adjacent the juncture of the front cylindrical section and the frusto-conical section and holes in the rear portions of the barrel, a rib cast in the bottom and interior of the barrel, the casting being 110 formed into a valve chamber at the rear of the barrel and into a neck for fitting onto the burner stem and a passage-way being provided through the neck through the rib and to the valve chamber. 115

In witness whereof we have hereunto set our hands on the 16th day of July, 1918.

EDWARD J. HORN.
FREDERICK LINDHORST.
